UNITED STATES PATENT OFFICE.

EILERT ALFRED CLEMENTS, OF GRAND RAPIDS, MICHIGAN.

UNDERWEAR.

1,298,667.

Specification of Letters Patent.

Patented Apr. 1, 1919.

Application filed August 23, 1918. Serial No. 251,129.

To all whom it may concern:

Be it known that I, EILERT ALFRED CLEMENTS, a citizen of the United States of America, residing at Grand Rapids, in the county 5 of Kent and State of Michigan, have invented certain new and useful Improvements in Underwear; and I do hereby declare the following to be a full, clear, and exact description of the invention, such as 10 will enable others skilled in the art to which it appertains to make and use the same.

The present invention relates to under-garments, being particularly concerned with certain constructions and improvements associated with the cuffs attached at the ends 15 of the legs of under-garments. The primary object and purpose of the invention is to provide a means associated with said cuffs at the ends of the legs of under-garments such that when hosiery of any kind 20 is drawn over said cuffs, an additional frictional means of connection is made between the garment and the hosiery which normally will hold the hosiery, such as socks or the 25 like, from working down, it having been practically necessary heretofore to use some kind of garter or equivalent hose supporting means to hold hosiery, particularly that of short length such as socks, against this 30 downward movement. Specifically, the invention consists in the provision of outstanding spaced apart ribs applied to said cuffs and passing entirely around the same in substantially horizontal planes, these ribs or 35 ridges serving to make a much greater frictional engagement with the hosiery, such as socks or the like, to hold the same in place.

For an understanding of the invention, reference may be had to the accompanying 40 drawing in which:

Figure 1 is a perspective view of a garment, my invention being used in connection therewith.

Fig. 2 is an elevation of a fabric section 45 from which a cuff may be made, and

Fig. 3 is a section therethrough.

Like reference characters refer to like parts in the different views of the drawing.

There is shown a union suit 1 of under-wear, though it is to be understood that the 50 invention is applicable to the lower garment

of a divided suit quite as well. To each of the legs 2 of the garment, at the lower end thereof, a cuff 3 is attached which at slightly spaced apart intervals is provided with a 55 plurality of outwardly projecting ridges 4 which pass entirely around the cuff, as shown. In practice the cuff portions to be attached at the lower ends of the legs of under-garments are usually knitted in tubular form on a suitable machine which, at intervals, corresponding to the desired length of the cuff, is formed with an outstanding ridge such as indicated at 4 in Fig. 3. By proper adjustment of the cuff knitting machine, these ridges can be made at much closer intervals or as close as desired for the working of my invention. On the inner side the cuff has a smooth surface so that no ridges or projections are brought directly 70 against the wearer. Of course it is to be understood that the formation of these outstanding spaced apart ridges may be made in a great variety of ways, it not being necessarily essential that the same shall be made 75 on a cuff knitting machine, though such manner of knitting is one very practical and convenient. But my invention contemplates the formation of the spaced apart surrounding ridges on the cuffs at the lower ends of 80 the legs of underwear garments irrespective of the manner in which the same are formed on the cuffs and in whatever way accomplished.

The invention is very simple but is particularly effective as has been proven by actual service. The elimination of hose supporters is accomplished thereby and the cost of manufacture of a garment equipped with my invention is practically the same as one 90 made as heretofore, having a smooth outer surface to the leg cuffs.

I claim:

A garment having legs, and a plurality of outstanding ribs located around and one 95 above the other a short distance and positioned in substantially parallel horizontal planes, substantially as and for the purposes described.

In testimony whereof I affix my signature. 100

EILERT ALFRED CLEMENTS.
